(57) **CLAIM**

The ornamental design for a straight firearm grip, as shown and described.

DESCRIPTION

FIG. 1 is a top front perspective view of a straight firearm grip, showing my new design;

FIG. 2 is a bottom rear perspective view thereof;

FIG. 3 is a front elevational view thereof;

FIG. 4 is a rear elevational view thereof;

FIG. 5 is a right elevational view thereof;

FIG. 6 is a left elevational view thereof;

FIG. 7 is a top plan view thereof;

FIG. 8 is a bottom plan view thereof;

FIG. 9 is a cross sectional view taken along line 9-9 in FIG. 4;

FIG. 10 is a reduced exploded top front perspective view thereof; and,

FIG. 11 is a reduced exploded bottom rear perspective view thereof.

The broken lines showing decorative patterns in FIGS. 1, 2, 5, 6, 10, and 11; mounting holes in FIGS. 1 and 7-10 and decorative ribs in FIGS. 1, 2, 4, 5, 6, 10, 11, are included for the purpose of illustrating environmental structure and form no part of the claimed design.

1 Claim, 8 Drawing Sheets
